(57) **CLAIM**

The ornamental design for a target stand, as shown and described.

DESCRIPTION

FIG. 1 is a perspective view of the preferred embodiment of the target stand incorporating my new design;

FIG. 2 is a front view thereof;

FIG. 3 is a rear view thereof;

FIG. 4 is a top view thereof;

FIG. 5 is a bottom view thereof; and,

FIG. 6 is an end view thereof with the opposite end being a mirror image.

The target stand is for holding an upright target.
